COMPUTER FOR USE IN DETERMINING THE TERMS OF INSTALLMENT FINANCING

Henry B. Case, 600 E. Jefferson, Plymouth, Ind.

Filed July 15, 1960, Ser. No. 61,372

Term of patent 14 years

(Cl. D52—1)

FIG. 5

FIG. 7

FIG. 6

FIG. 8

FIGURE 1 is a front elevational view of a computer for use in determining the terms of installment financing showing my new design;

FIGURE 2 is a top plan view;

FIGURE 3 is a bottom plan view;

FIGURE 4 is a side elevational view;

FIGURE 5 is a back elevational view;

FIGURE 6 is an enlarged cross-sectional view taken along line 6—6 of FIGURE 1 showing part of one computing strip;

FIGURE 7 is an enlarged cross-sectional view taken along line 7—7 of FIGURE 1 showing part of the other computing strip; and

FIGURE 8 is an enlarged fragmentary front view.

It is understood that the full line perforations shown are repeated throughout the area indicated in the draw-

ings. My design for a computer is characterized by the frame having the numerals disposed on the inner edges thereof on two adjoining edges, in association with the perforated chart and strip.

I claim:

The ornamental design for a computer for use in determining the terms of installment financing as shown and described.
